CLAIM

The ornamental design for an ultrasonic humidifier, as shown and described.

DESCRIPTION

1.1 is a front view of an ultrasonic humidifier showing our new design.

1.2 is a rear view thereof.

1.3 is a left side view thereof.

1.4 is a right side view thereof.

1.5 is a top view thereof.

1.6 is a bottom view thereof.

1.7 is a perspective view thereof.

(Continued)

The features shown in broken lines form no part of the claimed design.

1 Claim, 7 Drawing Sheets
